(57) **CLAIM**

I claim the ornamental design for a compressor shroud, as shown and described.

DESCRIPTION

FIG. 1 is a perspective view of a compressor shroud showing my new design;

FIG. 2 is a different perspective view of the shroud;

FIG. 3 is a side view of the shroud;

FIG. 4 is an opposite side view of the shroud;

FIG. 5 is a top view of the shroud;

FIG. 6 is a bottom view of the shroud;

FIG. 7 is a front view of the shroud;

FIG. 8 is a rear view of the shroud;

FIG. 9 is a perspective view of a compressor shroud showing a second embodiment of my new design;

FIG. 10 is a different perspective view of the shroud of FIG. 9;

FIG. 11 is a side view of the shroud of FIG. 9;

FIG. 12 is an opposite side view of the shroud of FIG. 9;

FIG. 13 is a top view of the shroud of FIG. 9;

FIG. 14 is a bottom view of the shroud of FIG. 9;

FIG. 15 is a front view of the shroud of FIG. 9; and,

FIG. 16 is a rear view of the shroud of FIG. 9.

The broken lines in FIGS. 1-8 are for illustrative purposes only and form no part of the claimed design.
